CLAIM

The ornamental design for a compressor wheel, as shown and described.

DESCRIPTION

FIG. 1 is a top perspective view of a compressor wheel in accordance with one embodiment of the present invention; FIG. 2 is a top plan view of the compressor wheel in FIG. 1; and,

FIG. 3 is an elevational side view, which is identical to the front and rear views, of the compressor wheel in FIG. 1. The dot-dot-dash broken lines shown in the drawings depict the surface contouring of the compressor wheel.
